CLAIM

The ornamental design for a mat, as shown and described.

DESCRIPTION

FIG. 1 is a top perspective view of the first embodiment of a mat, showing my new design;

FIG. 2 is top view thereof;

FIG. 3 is a bottom view thereof;

FIG. 4 is a front view thereof;

FIG. 5 is a rear view thereof;

FIG. 6 is a side view thereof;

FIG. 7 is an opposite side view thereof;

FIG. 8 is an enlarged detailed view of the encircled area 8 in FIG. 2;

FIG. 9 is an enlarged detailed view of the encircled area 9 in FIG. 3;

FIG. 10 is an enlarged detailed view of the encircled area 10 in FIG. 4;

FIG. 11 is a top perspective view of the second embodiment of a mat, showing my new design;

FIG. 12 is top view thereof;

FIG. 13 is a bottom view thereof;

FIG. 14 is a front view thereof;

FIG. 15 is a rear view thereof;

FIG. 16 is a side view thereof;

FIG. 17 is an opposite side view thereof;

FIG. 18 is an enlarged detailed view of the encircled area 18 in FIG. 12;

FIG. 19 is an enlarged detailed view of the encircled area 19 in FIG. 13; and,

FIG. 20 is an enlarged detailed view of the encircled area 20 in FIG. 14.
